[57] CLAIM

The ornamental design for a cooking grill, as shown and described.

DESCRIPTION

FIG. 1 is an upper front perspective view of the cooking grill showing my new design;

FIG. 2 is a top plan view thereof;

FIG. 3 is a front elevational view thereof;

FIG. 4 is a bottom view thereof;

FIG. 5 is a rear elevational view thereof;

FIG. 6 is a right side elevational view thereof; and,

FIG. 7 is a left side elevational view thereof.

The cooking grill is shown cut away to indicate indeterminate length and width.
